UNITED STATES PATENT OFFICE.

ELIJAH HOLMES, OF LYNN, MASSACHUSETTS.

PEG-CUTTER.

SPECIFICATION forming part of Letters Patent No. 225,285, dated March 9, 1880.

Application filed January 5, 1880.

To all whom it may concern:

Be it known that I, ELIJAH HOLMES, of Lynn, in the county of Essex and State of Massachusetts, have invented a new and useful Improvement in Peg-Cutters, which invention is fully set forth in the following specification, reference being had to the accompanying drawings.

My invention relates to counter peg-cutters; and it consists in a laminated cutter composed of layers of cutting-blades constructed and combined substantially as hereinafter described.

In the accompanying drawings, Figure 1 is a plan of my improved cutter. Fig. 2 is a vertical section of the same on line *x x*, Fig. 1. *A* is a cutter-bed, upon which a series of cutting-blades, 1 2 3 4 5, are mounted. This bed is formed and designed to be attached to the socket-shank of a counter peg-cutter in the usual manner by a pivot extending from such shank through said bed at *b*. The bed is also recessed at *c* and *d* to receive the usual locking slide or spring which is attached to the shank, to secure such swivel-bed in working position on its pivot; and projecting upward from the bed is a rectangular hub, *e*, upon and around which the cutting-blades, being provided with corresponding holes, are placed, one above the other, as shown. A central screw, *B*, is threaded in said bed through hub *e*, the head of the screw being countersunk in a rectangular block or washer, *f*, which serves to clamp the blades upon the hub and bed when screwed down upon the same, as shown.

The blades 1 2 3 4 5 are constructed of plates of sheet-steel of uniform width and thickness, but of gradually diminished lengths from 1 to 5, the ends whereof are bent obliquely, as shown, so as to form a series of upward-projecting cutting-edges gradually increasing in height above the bed from 1 to 5, such edges being rounded at their corners to protect the upper of the boot or shoe in which they are employed from injury.

A peg-cutter so constructed possesses the advantages of greater effectiveness in use, convenience in sharpening, and in case a blade gets broken or otherwise unfitted for use it is easily replaced without requiring an entire new cutter. These blades also furnish a greater depth of wearing-edge, are less liable to loss and damage in tempering, and in operation have a better clearance than cutters formed in or upon a solid plate in the usual manner.

I claim as my invention—

1. A laminated peg-cutter composed of a series of bent blades, 1 2 3 4 5, mounted upon a bed, *A*, and secured thereto, substantially as and for the purposes specified.

2. The bed *A*, provided with a hub, *e*, a pivot-hole, *b*, and recessed at *c* and *d*, in combination with a series of detachable blades mounted thereon and secured thereto, substantially as and for the purposes specified.

ELIJAH HOLMES.
